GAME BOARD FOR RECEIVING GAME PIECES

Marinus Yantes, 3446 Queen Ave. N., Minneapolis, Minn.

Filed Dec. 4, 1963, Ser. No. 77,652

Term of patent 3½ years

(Cl. D34—5)

FIG. 2

I claim:

The ornamental design for a game board for receiving game pieces, as shown.
